UNITED STATES PATENT OFFICE

ARTHUR SCOTT, OF CLEVELAND, OHIO, ASSIGNOR TO THE CLEVELAND PNEUMATIC TOOL COMPANY, OF CLEVELAND, OHIO, A CORPORATION OF OHIO

REMOTE CONTROL FOR FLUID MOTORS

Application filed February 3, 1927. Serial No. 165,658.

This invention relates to a remote control for fluid motors, having reference particularly to means for reversing the direction of rotation of the power shaft of the motor by manipulation at a point distant from the motor itself.

Compressed air motors are sometimes employed for performing operations of various kinds in situations where the motor is not accessible to the operator, as for instance, where there are extremely high temperatures. In such cases, rendering it impossible for the operator to approach the motor closely, the hand control ordinarily employed for starting, stopping and reversing the motor cannot be used. Furthermore, it is impractical to locate such a hand control at a distance from the motor, for the reason that any attempt to lead the exhaust to a point distant from the motor always results in strangling it, which reacts upon the power of the motor.

One object of the present invention, therefore, is the provision of a remote control for fluid motors acting through the motive fluid itself to change the direction of rotation of the motor.

Other objects, and objects relating to details of construction and economies of manufacture, will appear as I proceed with the description of that embodiment of the invention which, for the purposes of the present application, I have illustrated in the accompanying drawings, in which:

Fig. 1 is a more or less diagrammatic view illustrating an air motor with my improved reversing valve attached thereto and with pipe connections leading from the said valve to a manual control valve located at a distance from the motor;

Fig. 2 is a detail plan view showing a handle which may be employed in connection with the four-way valve;

Fig. 3 is a section taken diametrically through the reversing valve on a plane parallel to the plane of Fig. 1, and

Fig. 4 is a detail cross sectional view taken substantially on the line 4-4 of Fig. 3.

Similar reference characters refer to like parts throughout the views.

In the drawings, 10 represents a reversible

compressed air motor which may be of any desired internal construction so long as there is incorporated in it a fluid passage 11 and a fluid passage 12 connected with an annular passage 13, the two passages 11 and 12 acting interchangeably as inlet and exhaust passages, depending upon the direction of rotation of the motor. Upon the motor drive shaft 14, I mount a pinion 15 which may be caused to mesh with a gear or rack, not shown, upon the machine or apparatus desired to be actuated.

In one end of the motor casing is a threaded opening into which is screwed the threaded end of the casing member 18 of my automatic reversing valve. The central extension 19 of the casing is beveled on its end to fit into a beveled socket 20 in the motor and to form a fluid-tight joint therewith when the casing member 18 is threaded home. A lock nut 21 helps to prevent these parts from becoming loosened. The reversing valve casing or shell is provided with a fluid passage 22 which runs through the extension 19, and with a second fluid passage 23, which terminates at the end of the casing member outside the extension 19. When the parts are assembled, the passage 22 forms a continuation of the passage 11 of the motor and the passage 23 opens into the annular passage 13 of the motor which connects with the passages 12 and 12'. In the motor there are passages 50 and 51 connecting respectively with passages 12 and 12'. A rotary valve 52 serves to connect at properly timed intervals the passage 11 and the passages 50 and 51 with the ports of the motor cylinders. The detailed arrangement of the internal passages connecting the rotary valve 52 with the cylinder ports, is not here illustrated as the present invention has nothing to do with the motor construction per se, it being essential merely that the construction be such as to cause reversal of rotation when the valve mechanism, presently to be described, is operated to reverse the direction of flow in the passage 11 on the one hand and the passages 12 and 12' on the other hand.

At its opposite end the casing 18 is bored out to receive with a driving fit a barrel 24 in which is mounted to slide, a spool valve 25.

having heads 26 and 27. As shown in Fig. 3, the barrel 24 has a pair of holes 28 and 29 near one end and a pair of holes 30 and 31 near the other end, the first pair opening into 5 passage 23 and the second pair into passage 22. These holes are adapted to be covered by the heads 27 and 26 respectively of the spool valve. The end of the bore made for the insertion of barrel 24 is closed preferably by a 10 hollow plug 32 which has a cavity 33 connected by four equally spaced holes 34 with an annular passage 35, the cavity 33 opening through a central bore 36 into the interior of the barrel 24. The cavity 33 is closed by a 15 solid tapered plug 37.

The valve has a common exhaust port 38 and intake ports 39 and 40, the exhaust port 38 extending through the valve casing and through the barrel 24, the intake port 39 20 extending through the casing and making connection with the interior of the barrel 24 through an axial bore 41 in the casing, and the intake port 40 opening into the annular passage 35 of the plug 32 and thence by passages 34, 33 and 36 into the interior of the barrel 24. The port 38 opens, preferably, directly to atmosphere. The intake ports 39 25 and 40 are connected by relatively long pipes 42 and 43, flexible or otherwise, to a valve 44 which acts to direct the motive fluid from supply pipe 45 to either of said pipes 42 and 43 or to cut off communication between said pipe 45 and the motor. I have illustrated for 30 this purpose a four-way valve with one port 46 opening to atmosphere, so that such slight pressure as might tend to remain in the inactive one of the pipes 42 and 43 can be quickly dissipated when the position of valve 44 is changed. It should be understood, however, 35 that the detail construction of valve 44 is immaterial and may be varied to suit conditions. In Fig. 2 I have illustrated a control handle 47, the construction of which will be obvious from the drawings, for conveniently operating 40 the valve 44.

Operation: Assuming that the valve handle 47 is in the "stop" position and that it is desired to drive the pinion 15 in one direction, which may be considered the forward 45 direction, the handle 47 is shifted to the position illustrated in Fig. 2, placing the passages of valve 44 in the position shown in Fig. 1, whereupon motive fluid will flow from pipe 45 into pipe 43 and thence into intake port 39 and through bore 41, striking 50 against head 27 of spool valve 25 shifting it to the left, as shown in Fig. 3, and holding it there while the motive fluid passes out through hole 29 into passage 23 and thence 55 through passages 13 and 12 into the motor to drive the latter in the desired direction. The exhaust from the motor returns through motor passage 11 and valve passage 22 and flows through hole 30 into the barrel 24 and 60 out through common exhaust port 38.

Now, should it be desired to reverse the direction of rotation of the motor, the handle 47 is moved first to "stop" position, and then to the reverse position indicated in Fig. 2, thus moving the valve piece of valve 44 90° 70 clockwise and bring supply pipe 45 into communication with pipe 42 and pipe 43 into communication with the atmosphere through port 46 in valve 44. Motive fluid now flows through pipe 42, port 40, annular passage 35, 75 and passages 34, 33 and 36, striking against head 31 of the spool valve shifting it to the right to close off holes 29 and 30 and to open holes 28 and 31. The incoming fluid then flows through hole 31 and passage 22 into 80 the motor passage 11, and the exhaust from the motor returns through motor passages 12 and 13 into valve passage 23 and through hole 28 to common exhaust port 38.

While I have described my invention with 85 more or less particularity, I appreciate that changes in design and proportions can be resorted to without departing from the spirit of the invention, and I do not desire to be bound by any limitations other than those included in the appended claims. 90

Having thus described my invention, what I claim is:

1. A reversible rotary fluid pressure motor having a reversing valve operated by 95 fluid pressure, said reversing valve being arranged to be acted upon by the motive fluid passing to said motor, and means for causing fluid from a common source to take either one of two different courses in approaching 100 said reversing valve.

2. A reversible rotary fluid pressure motor having a remote controlled reversing valve adapted to be shifted by fluid pressure, said reversing valve being arranged to be acted 105 upon by the motive fluid passing to said motor, and means for causing fluid from a common source to take either one of two different courses in approaching said reversing valve. 110

3. In combination, a reversible fluid pressure motor having interchangeable intake and exhaust passages, valve mechanism in juxtaposition with the motor containing two passages connected respectively with the said motor passages, said valve mechanism having two separate inlet ports for motive fluid and a common exhaust port, a manual control valve, separate pipes extending from said inlet ports to said manual control valve, said valve being adapted to direct motive fluid into either of said pipes, said valve mechanism including means for connecting either of said valve passages to said common exhaust port when the pipe connected with the inlet port for the other passage is employed 120 to carry motive fluid. 125

4. In combination, a reversible fluid pressure motor having interchangeable intake and exhaust passages, valve mechanism in 130

- juxtaposition with the motor containing two passages connected respectively with the said motor passages, said valve mechanism having two separate inlet ports for motive fluid and a common exhaust port, a manual control valve, separate pipes extending from said inlet ports to said manual control valve, said valve being adapted to direct motive fluid into either of said pipes, said valve mechanism including means for selecting one or the other of said valve passages as the intake passage depending upon which of said pipes is employed to carry the motive fluid, said automatic means also connecting the remaining valve passage with the common exhaust port. 10
- 15 5. In combination, a reversible rotary shaft fluid pressure motor having interchangeable intake and exhaust passages, valve mechanism in juxtaposition with the motor containing two passages connected respectively with the said motor passages, said valve mechanism having two separate inlet ports and a common exhaust port, said valve mechanism including means for selecting one or the other of said valve passages as the intake passage, depending upon which of said inlet ports is employed, and for connecting the remaining passage with the common exhaust port, said means comprising conductors 25 for the motive fluid passing to said motor and means remotely controlled for directing motive fluid to either of said ports. 30
- 35 6. In a reversible rotary shaft fluid pressure motor, a reversing valve comprising a casing having two fluid passages, a spool valve, a barrel therefor, said barrel having an exhaust port in the middle and an intake port at each end, said barrel having also a pair of longitudinally spaced holes therethrough near one end opening into one fluid 40 passage and a pair of similar holes near its other end opening into the other fluid passage, said spool valve being adapted to be shifted to one end of said barrel by motive fluid introduced at the other end, said shifting movement uncovering the inner hole at one end of the barrel and the outer hole at the other whereby one passage is connected to the active intake port and the other passage 45 is connected to the common exhaust port. 50
- 55 7. In a valve mechanism of the class described, a spool valve, a barrel therefor, said barrel having an exhaust port at the middle and an inlet port at each end, said barrel also having in its side wall near each end a fluid intake hole and having an exhaust hole between each of said intake holes and the middle of the barrel whereby motive fluid entering through either of said inlet ports will 60 shift the spool valve to the other end of the barrel uncovering the intake hole in that end of the barrel which is near the active inlet port and uncovering the exhaust hole in the opposite end of the barrel. 65
8. In a valve mechanism of the class de- 65
- scribed, a shiftable valve, a casing therefor, said casing having inlet ports at spaced points and an exhaust port at an intermediate point, said casing having also near each inlet port a fluid intake hole and having an exhaust 70 hole between each intake hole and the said exhaust port whereby motive fluid entering through either of said inlet ports will shift the said valve to one extreme of its motion in the direction of the other intake port, uncovering the intake hole near the first named intake port and uncovering the exhaust hole on the opposite side of the exhaust port. 75
- In testimony whereof, I hereunto affix my signature. 80
